ASH RECEIVER

Carl Rebholz, Milwaukee, Wis.

Application May 11, 1936, Serial No. 79,119

1 Claim. (Cl. 220—30)

This invention appertains to new and useful improvements in receptacles for ashes.

The principal object of the present invention is to provide an ash receiver which is constructed in such a manner as to be substantially fireproof.

Another important object of the invention is to provide an ash receiver which will maintain itself closed.

Another important object of the invention is to provide an ash receiver which is of stable and durable construction and not susceptible of becoming easily broken.

These and various other important objects and advantages of the invention will become apparent to the reader of the following specification.

In the drawings:—

Figure 1 represents a front elevational view of the receiver.

Figure 2 represents a vertical sectional view through the receiver.

Figure 3 is a top plan view of the receiver with a portion of the front broken away.

Figure 4 is a fragmentary detailed sectional view taken substantially on the line 4—4 of Figure 3.

Figure 5 is a sectional view taken substantially on the line 5—5 of Figure 1.

Figure 6 is a fragmentary side elevational view of the receiver.

Referring to the drawings wherein like numerals designate like parts, it can be seen that the receiver is made up of the bottom 5, back wall 6, side walls 7—7, front wall 8 and top wall 9. The top and bottom walls 9—5 are provided with groove-ways 10 therein to receive the upper and lower edges of the back, side and front walls 6, 7, and 8.

As is clearly shown in Figure 3, the top wall 9 has a substantially square opening 11 therein in which the rockable closure 12 is mounted.

In forming the top 9, the copper tube 13 is molded or embedded therein and aligned with this tube 13 on the opposite side of the opening 11 from the tube is the nut 14 which is embedded in the top 9, it being understood that the top, bottom and side walls as well as the front and rear walls are of a cementitious mixture. The closure 12 is likewise provided with a copper tube 15 dis-

posed therethrough and aligned with the nut 14 and tube 13.

Through these tubes 13—15 is disposed the rod 16 for swingably supporting the closure 12. One end of this rod 16 is provided with threads 5 for engagement in the nut 14 while the other end is provided with a screw-driver receiving slot 17.

Nuts 18 are embedded in the side edges of the end walls 7—7 to receive bolts 19 driven through the front and rear walls 8—7.

As can be seen in Figure 2, the edges of the top 9 at the opening 14 as well as the closure 12 are provided with abutting flanges 20 and one end portion of the closure 12 is provided with a counter-balancing enlargement 21 for maintaining the closure normally in closed position.

The front wall 8 is provided with an opening 22 therein in which the emptying door 23 is mounted. A rod 24 is disposed through one end portion of this door 23 and has its ends journaled in bearings 20 25 embedded in the front wall 8 and bottom wall 5. (See Figure 1.)

A suitable latch 26 at the opposite end of the door 23 permits the door to be fastened to maintain the ashes in the receptacle.

While the foregoing specification sets forth the invention in specific terms, it is to be understood that numerous changes in the shape, size and materials may be resorted to without departing from the spirit and scope of the invention as claimed hereinafter.

Having described the invention what is claimed as new is:—

An ash receptacle comprising a box-like construction of cementitious material, said box-like structure having an opening in the top thereof, a closure for said opening and means for swingably supporting the said closure, said means for swingably supporting the closure consisting of a tube embedded in the closure, a tube embedded in the top of the box-like structure and extending to the edge thereof and aligned with the tube of the closure, a nut embedded in the top of the box-like structure and aligned with the said tube, a rod provided with threads at one end disposed through the said tubes and engaged into the said nut, and means at the opposite end of the rod whereby the rod can be rotated.

CARL REBHLZ.
